UNITED STATES PATENT OFFICE.

FRANCIS G. GALE, OF WATERVILLE, QUEBEC, CANADA.

BEDSTEAD.

No. 842,879.

Specification of Letters Patent.

Patented Feb. 5, 1907.

Application filed April 27, 1906. Serial No. 314,035.

To all whom it may concern:

Be it known that I, FRANCIS G. GALE, a subject of the King of Great Britain, residing at Waterville, Province of Quebec, Canada, have invented an Improvement in Bedsteads, of which the following description, in connection with the accompanying drawings, is a specification, like numerals on the drawings representing like parts.

10 This invention relates to bedsteads, and especially to iron bedsteads.

It has for its object to provide a novel construction wherein an iron bedstead may be provided with brass trimmings and especially 15 with brass top rails with less expense than as heretofore constructed.

Usually the brass top rails of the end frames of iron bedsteads extend from one post to the other of each end frame, and 20 these brass top rails are secured to the posts by means of especially made connections which involve more or less expense in their manufacture. In order to eliminate the expense involved in these special fittings, I 25 have devised an end frame for an iron bedstead in which the posts are provided with arms between which the brass top rail is held without the use of any special fittings or connections and simply by the resiliency of the 30 material of the bed-frame. The arms above referred to form, in effect, part of a top rail and are in line with the brass trimming which constitutes the main portion of the top rail. In this way a saving is effected, first, by the 35 elimination of the special fittings necessary to connect the top rail to the posts, and, second, because the brass portion of the top rail does not extend entirely across from one post to the other, and consequently less brass 40 (which is the expensive material) is used than with the old construction.

A bedstead made according to my invention has substantially as elegant appearance as one in which the brass top rail extends 45 clear from one side to the other.

In the drawings, Figure 1 is a view of a bedstead embodying my invention. Fig. 2 is a view, on a large scale, of a portion of an end frame, part of the end frame being shown 50 in section to better illustrate the invention.

The end frames of the bed are designated by 3 and 4, respectively, and each is made with a corner-post 5 and may be provided with the intermediate rods 6, which may 55 either be vertical rods or may have any desired configuration. In the drawings these

rods 6 are shown as vertical rods and at their lower ends are connected to the lower rail 7 of the end frame.

The corner-posts 5 have extending therefrom arms 9, and in this embodiment of my invention these arms are connected by the dropped rod or connection 10, said connection 10 being secured to the upper ends of certain of the vertical rods 6.

60 The corner-posts, the arms 9, the lower rail 7, the dropped or downwardly-bent rod 10, and the vertical rod 6 are all made as one integral structure, and these parts are connected together by the "chills" 21, which are 70 cast about the points of junction between the parts, all as usual in the manufacture of iron bedsteads.

75 11 designates the brass top rail, and it is made to extend between the arms 9. The top rail is preferably tubular, and at its end it sets over the tips 12, extending either from the ends of the arms 9 or from chills 21 cast thereon.

80 In applying the brass top rail to the end frame the arms 9 are spread apart sufficiently by any suitable implement to permit the brass top rail to be inserted between them, and after the brass top rail is in place the resiliency of the end frame causes the arms to 85 move toward each other sufficiently to cause the projections 12 to enter the ends of the tubular brass top rail.

90 It will be seen that the brass top rail is merely sprung into place and that it is held in position without any special fittings or connections and merely by the resiliency of the end frame and the interlocking connection between the tips 12 and the brass top rail.

95 The arms 9 may be of any desired length—that is, they may be so short as to be hardly noticeable—in which case the brass top rail 11 will extend from one post to the other, or said arms may be made with more or less 100 length, as shown in the drawings, in which case the brass top rail extends substantially, but not entirely, across the end frame. In either event the bedstead when completed has all the appearance of one in which a brass 105 top rail extending from one post to the other is used, and yet a material saving in expense is secured not only by the elimination of special fittings to secure the brass top rail to the posts, but also because a shorter brass section 110 may be used than when the brass top rail extends the full length of the end frame.

If desired, the brass top rail may have any suitable ornamentation—as, for instance, a pillar or post 14. In the form of the invention herein shown the arms 9 form continuations of the posts 5 and are made by bending the posts inwardly. In many bedsteads, however, the posts extend slightly above the top rail and are ornamented with brass knobs. In embodying my invention in this type of bedstead the arms would not form continuations of the corner-posts, but would be made integral therewith and project therefrom.

I have shown herein one embodiment only of my invention, and it will be obvious that 15 the shape and configuration may differ without departing from the invention.

Having fully described my invention, what I claim as new, and desire to secure by Letters Patent, is—

- 20 1. An end frame for a bedstead having two connected corner-posts capable of being sprung apart slightly and a top rail held between said corner-posts by the resiliency of the end frame.
- 25 2. An end frame for a bedstead having two connected corner-posts capable of being sprung apart and each provided with a projection and a top rail having a socket in its ends to fit over said projections.
- 30 3. An end frame for a bedstead having two

corner-posts each provided with an arm, said corner-posts being resiliently connected, and a brass top rail movably sustained between said arms.

4. In a bedstead, an end frame having two 35 corner-posts, arms extending therefrom, each provided with a projection, and a brass top rail extending between said arms, said top rail having sockets in its ends to fit over said projections.

5. In a bedstead, an end frame having two corner-posts, an arm extending inwardly from each corner-post, a dropped rod connecting said arms, and a brass top rail detachably sustained by the arms.

6. In a bedstead, an end frame comprising two corner-posts each having an arm extending inwardly therefrom, provided with a projection, a dropped rod connecting said arms, and a tubular top rail extending between 50 said arms, the projections on the arms entering the ends of said top rail.

In testimony whereof I have signed my name to this specification in the presence of two subscribing witnesses.

FRANCIS G. GALE.
